J. Stuart Freeman,
Attorney

UNITED STATES PATENT OFFICE.

MAURICE ALLAND, OF ATLANTIC CITY, NEW JERSEY.

SMOKER'S PIPE.

Application filed April 14, 1923. Serial No. 632,044.

The object of this invention is to provide certain improvements in smokers' pipes and attachments therefor, and throughout the following specification the term "pipes" is to be understood as applying to and anticipating any article usable by a person to contain or support tobacco or other material in order to smoke the same, either in the form of loose particles, such as smoking tobacco, or assembled into a predetermined shape, as for instance cigars and cigarettes.

Such articles are of various forms wherever smoking is practiced, but in this country they generally assume the form of pipes and tubular cigarette-holders, each essentially comprising a recess adapted to receive the loose or formed tobacco, an end portion adapted to be held between the lips, and a conduit connecting the recess with the mouth portion, whereby smoke from the burning tobacco is drawn from the recess into the mouth.

In practice the smoke and gases of combustion from the burning tobacco, or other material from the smoking of which pleasure may be obtained, tend to burn the tongue and blister the same, as well as causing a certain degree of discomfort during warm weather due to the temperature of the gases affecting the bodily temperature of the smoker. It is therefore highly desirable to produce what is known as a "cool smoke," that is, to provide one with the quality of smoke desired, but at such temperature that no discomfort will ensue therefrom.

The present invention therefore has for an object to provide a pipe, cigarette-holder, or the like, with an aperture extending laterally from the exterior into the conduit leading from the tobacco-containing recess to the mouth portion of the device, together with a specially designed valve of simple yet highly efficient construction and operation, whereby cool air can be drawn through the said conduit along with the smoke from the said recess, or need not, as may be desired, and when so drawn the relative quantity of air entering the said conduit and uniting with the smoke can be regulated to a nicety.

With these and other objects in view, the present invention comprises further novel details of construction and operation herein-after fully brought out in the following description when read in conjunction with the accompanying drawings, in which Fig. 1 is a side elevation of a smoker's pipe comprising

one embodiment of the invention; Fig. 2 is an enlarged fragmentary section on the line 2-2 of Fig. 1; Fig. 3 is an enlarged front elevation of the valve shown in Figs. 1 and 2; Fig. 4 is a transverse section of the valve shown on the line 4-4 of Fig. 2; Fig. 5 is a similar section on the line 5-5 of Fig. 2; and Fig. 6 is an elevational view similar to Fig. 3, but showing the valve partially closed.

Referring to the drawings, a pipe is shown as comprising the usual bowl 1, in which particles of tobacco are adapted to be inserted, but which is also intended to represent the recess of any smokers' article adapted to receive tobacco or other smoking material in any form, such for instance as the cigarette-containing recess of the cigarette-holder. The pipe illustrated furthermore comprises the stem 2, extending laterally from one side of the bowl and tapering therefrom, it being provided upon its smaller end with a suitably shaped mouth-piece or mouth-engaging portion 3. Through the stem and mouth portion extends a conduit leading from the lower portion of the bowl and provided for the purpose of conducting smoke and gases of combustion from the tobacco within the bowl toward and through the said mouth-engaging portion.

At any desired position upon the stem 2, a laterally directed aperture 4 is provided, which leads from the exterior into the conduit 5. Into said aperture is adapted to be inserted the substantially cylindrical neck portion 6 of a valve, said neck portion being provided with an axial bore 7, and terminating outwardly in a substantially plane section 8, provided around its periphery with a substantially cylindrical flange 9, interrupted at one portion by an aperture 10. It will also be noted that that portion of the section 8, contiguous to and in alignment with, said aperture 10 is bent slightly rearwardly to form a lug 11.

Within the valve-casing thus formed and abutting against the radially outer portion of the said plane section 8 is an annular gasket 12 of yielding material such as rubber or the like. Positioned in uniform contact with the said gasket is a disc 13 provided with any desired number of spaced apertures 14, and at one point of its periphery it is also provided with a radially extending projection 15 normally lying in the

aperture 10 and co-operating with the side walls defining the circumferential limits of said aperture to prevent said disc from revolving with respect to the surrounding 5 valve-casing.

A cap is provided for said valve-casing and the contents thereof, said valve comprising a preferably slightly concaved central portion 16, surrounded by a substantially cylindrical portion 17, which may be provided upon its outer surface with suitable knurling 18 if desired, said cylindrical portion slidably engaging and being rotatable about the outer surface of the cylindrical portion 9 of the valve-casing and at its marginal portion being turned radially inwardly to provide a flange 19 embracing a portion of the rear surface of the plane section 8 of said casing.

20 The flange portion 19 is cut away at 20, the laterally opposite sides of which cut-away portion co-operate in turn with the opposite sides of the lug 11 for limiting the movement of the cap as the same is oscillated with respect to the casing. Said cap is furthermore provided with spaced apertures 21, which, when positioned as shown in Fig. 3, coincide with the apertures 14 in the disc 13, and offer a relatively free passage for air through said aligned apertures by way of the gasket 12 and thence through the apertures 7 in the neck portion 6 of the valve-casing, towards and into the bore 5 of the pipe-stem, where the cool fresh air unites with the relatively hot smoke and gases of combustion from the tobacco being consumed within the bowl 1, and pass towards and through the mouth portion 3 of the pipe.

40 If it is desired to shut off the supply of fresh air through the valve structure, the cap is oscillated so that the apertures 21 and 14 are out of alignment, thereby making it possible to smoke with the pipe equipped with the improved valve exactly as though there were no valve carried by the pipe, and the usual hot smoke is received in the mouth of the smoker. Obviously then, it is possible to oscillate the cap but a relatively short distance as shown in Fig. 6, wherein the apertures 21 and 14 are but partially in alignment and permit a varying degree of cool fresh air to enter the pipe-stem between the zero and maximum limits 50 before referred to.

It will also be noted that this valve structure is so positioned upon the pipe-stem that for either a right or left handed person a finger or thumb can without awkwardness, 60 but in a purely natural manner, be placed over the valve-cap, and the latter being concaved to fit the curvature of one's finger, the same will conveniently rest in that position, with the result that when the valve is either 65 completely or partially opened, said finger

or thumb may be used to manually obstruct the openings 21, and in effect more nearly or entirely close the valve intermittently, or as often and to the exact extent as may be desired without necessitating alteration of 70 the valve-cap with respect to the casing.

It will also be noted from the structure herein described and illustrated that an air-tight valve has been provided, whereby air can bypass into the pipe or cigarette-holder 75 stem only through the combined apertures 14 and 21, and not around the periphery of the cap, thus providing a positive control for the air, either by positioning the valve-cap as desired or by manually obstructing 80 the valve openings to a greater or less degree as before described.

Having thus described my invention, what I claim and desire to protect by Letters Patent of the United States is:—

1. A hollow valve casing having a neck, an annular gasket within the said casing, a perforated disc also within the said casing and seated against said gasket, and a perforated cap covering the open end of the 85 said casing and embracing the periphery thereof, said cap being oscillatable so that the two sets of perforations register or variably close each other to alter the passage of air through said valve.

2. A valve comprising an apertured neck portion, a plane portion formed integrally with said neck portion, said plane portion terminating radially in a cylindrical portion, an annular gasket fitted within said 100 cylindrical portion and against said plane portion, a perforated disc resting against said gasket, and a perforated cap having a peripheral flange encircling the cylindrical portion of the casing and oscillatable with 105 respect thereto.

3. A valve comprising an apertured neck portion, a plane portion formed integrally with said neck portion, said plane portion terminating radially in a cylindrical portion, an annular gasket fitted within said 110 cylindrical portion and against said plane portion, a perforated disc resting against said gasket, a perforated cap having a peripheral flange encircling the cylindrical 115 portion of the casing and oscillatable with respect thereto, and a radial extension carried by said disc engaging the sides of a recess in the cylindrical portion of the casing, to prevent movement of the disc with respect to said casing.

4. A valve comprising an apertured neck portion, a plane portion formed integrally with said neck portion, said plane portion terminating radially in a cylindrical portion, an annular gasket fitted within said 125 cylindrical portion and against said plane portion, a perforated disc resting against said gasket, a perforated cap having a peripheral flange encircling the cylindrical 130

portion of the casing and oscillatable with respect thereto, a section of said cylindrical portion having a recess, and a lug being formed on said plane portion in alignment 5 with the recess, a radial extension carried by said disc and extending into said recess to prevent movement of the disc with respect to the casing, the marginal portion of the cap being flanged around the rear of said 10 plane portion and also having a recess, said lug extending into the recess of the flange and engaging the same to predetermine the limit of oscillation of said cap.

5. A valve, adapted for use to bypass air 15 into the conduit of a smoker's pipe, and comprising a hollow casing, having a body

portion surrounded by a cylindrical portion and having a recess, an apertured disc in said casing having a projection extending into and engaging the sides of said recess 20 to prevent circumferential movement of said disc, an apertured cap covering said disc and at its margin surrounding said cylindrical portion, said cap also having a recess and a lug carried by said body portion and 25 extending into the recess of the cap to predetermine the limit of oscillation of said cap.

In testimony whereof I have affixed my signature.

MAURICE ALLAND.
